LADY'S HANDBAG OR SIMILAR ARTICLE

Floyd J. Hurst, Gainesville, Tex.

Application April 19, 1954, Serial No. 30,070

Term of patent 14 years

(Cl. D87—3)

To all whom it may concern:

Be it known that I, Floyd J. Hurst, a citizen of the United States, residing at Gainesville, Cooke County, Texas, have invented a new, original, and ornamental Design for a Lady's Handbag or Similar Article, of which the following is a specification, reference being had to the accompanying drawing, forming a part hereof.

I claim:

The ornamental design for a lady's handbag or similar article, as shown.
